[57] CLAIM

The ornamental design for a kettle, as shown and described.

DESCRIPTION

FIG. 1 is a top, front, and right side perspective view of a kettle showing my new design;

FIG. 2 is a right side elevational view of the kettle shown in FIG. 1, the left side of the kettle being a mirror image of the right side;

FIG. 3 is a top plan view of the kettle shown in FIG. 1;

FIG. 4 is a bottom plan view of the kettle shown in FIG. 1;

FIG. 5 is a front elevational view of the kettle shown in FIG. 1; and,

FIG. 6 is a rear elevational view of the kettle shown in FIG. 1.
